(57) **CLAIM**
The ornamental design for a sealing boot, as shown and described.

DESCRIPTION

FIG. 1 is a top, front perspective view of a sealing boot showing our new design;
FIG. 2 is a top, back perspective view thereof;
FIG. 3 is a top plan view thereof, the bottom plan view being a mirror image thereto;
FIG. 4 is a left side elevation view thereof, the right side elevation view being a mirror image thereto;
FIG. 5 is a front elevation view thereof; and,
FIG. 6 is a back elevation view thereof.
The broken line portion of the figure drawings is included to show unclaimed subject matter only and forms no part of the claimed design.
